(57) **CLAIM**

I Claim the ornamental design for a cooler insert, as shown and described.

DESCRIPTION

FIG. 1 shows a bottom perspective view of a cooler insert showing my new design;

FIG. 2 shows a top and side perspective view thereof; and, FIG. 3 shows a top perspective view thereof.

The oblique shading lines in the drawing depict surfaces that are translucent.

The broken lines in FIG. 1 depict portions of the cooler insert that form no part of the claimed design.
